(57) CLAIM

The ornamental design for a hat, as shown.

DESCRIPTION

FIG. 1 is a rear perspective view of a hat showing my new design.

FIG. 2 is a front perspective view thereof.

FIG. 3 is a top view thereof.

FIG. 4 is a bottom view thereof.

FIG. 5 is a front view thereof.

FIG. 6 is a rear view thereof.

FIG. 7 is a left side view thereof; and,

FIG. 8 is a right side view thereof.

In the drawings, the broken lines represent stitching forming part of the claimed design.
